UNITED STATES PATENT OFFICE

160,712

SWIMMING FLOAT

Neshad Kahn, Detroit, Mich.

Application March 20, 1950, Serial No. 8,659

Term of patent 14 years

(Cl. D71—1)

To all whom it may concern:

Be it known that I, Noshad Kahn, a citizen of the United States, residing at Detroit, in the county of Wayne and State of Michigan, have invented a new, original, and ornamental Design for a Swimming Float, of which the following is a specification, reference being had to the accompanying drawing, forming a part thereof.

In the drawing:

I claim:

The ornamental design for a swimming float, as shown.

NOSHAD KAHN.
